(57) **CLAIM**

The ornamental design for a pet playpen, as shown and described.

DESCRIPTION

FIG. 1 is a front, right, top perspective view of a pet playpen, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 2;

FIG. 11 is an enlarged view of detail 11 in FIG. 3;

FIG. 12 is an enlarged view of detail 12 in FIG. 5;

FIG. 13 is an enlarged view of detail 13 in FIG. 7;

FIG. 14 is an enlarged view of detail 14 in FIG. 8;

FIG. 15 is an enlarged view of detail 15 in FIG. 8;

FIG. 16 is a front, right, top perspective view at a reduced scale in an alternate configuration, shown in an environment of use.

FIG. 17 is an enlarged view of detail 17 in FIG. 16;

FIG. 18 is an enlarged view of detail 18 in FIG. 16;

FIG. 19 is an enlarged view of detail 19 in FIG. 16;

FIG. 20 is an enlarged view of detail 20 in FIG. 16;

FIG. 21 is an enlarged view of detail 21 in FIG. 16; and,

FIG. 22 is an enlarged view of detail 22 in FIG. 16.

The dashed broken lines in the figures are for the purposes of illustrating portions of the pet playpen and form no part of the claimed design. The figures from 16 to 22 are provided to show the claimed design in an environment of use.

The dash-dot-dash broken lines are for notating enlarged views and form no part of the claimed design.

1 Claim, 22 Drawing Sheets
